J. BARNES

THREAD TENSIONING MEANS

Filed July 10, 1923

Patented Nov. 17, 1925.

1,562,071

UNITED STATES PATENT OFFICE.

JOSEPH BARNES, OF NEW BEDFORD, MASSACHUSETTS, ASSIGNOR TO L. V. B. TENSION COMPANY, OF NEW BEDFORD, MASSACHUSETTS, A CORPORATION OF MASSACHUSETTS.

THREAD-TENSIONING MEANS.

Application filed July 10, 1923. Serial No. 650,637.

To all whom it may concern:

Be it known that I, JOSEPH BARNES, a citizen of the United States, residing at New Bedford, in the county of Bristol, State of Massachusetts, have invented a certain new and useful Improvement in Thread-Tensioning Means, of which the following is a specification, reference being had therein to the accompanying drawings.

10 The invention relates to tension devices such as those which are used for imparting the necessary tension to yarns, threads, and the like, in being wound, etc.

15 The invention comprises various improvements which have been designed primarily for application in connection with tension devices of the type of those shown and described in U. S. Letters Patent No. 1,356,926, dated Oct. 19, 1920, and No. 1,393,926, dated 20 Oct. 18, 1921.

Tension devices of the type just referred to comprise a bearing surface, bed, or backing, and a presser which is lightly borne toward such surface or bed, the yarn or thread 25 passing between the two. The later form of device which is illustrated in Patent No. 1,393,926, comprises a weighted presser-lever, and a yarn or thread-engaging presser 30 pivotally mounted on said presser-lever adjacent the opposing surface or bed, and having a yielding face making a two-point contact with the said surface or bed.

One drawback in the use of tension devices in general is a tendency to collection 35 of lint at a tension device, alongside the running yarn or thread, portions of such lint at intervals passing onward with the yarn or thread and sometimes remaining in the form of slubs or slugs attached thereto 40 as wound, with the result that when the wound yarn is used subsequently in the manufacture of cloth the character and quality of the latter are injured by the said slubs or slugs. One object of the present invention is to improve the tension devices of the 45 patents aforesaid so as to avoid this drawback by making effective provision adjacent the point or points of contact for escape of lint so that it does not collect at such points, and consequently cannot form slubs or slugs.

Another object of the invention is to render a tension device of the type of those of the Letters Patent aforesaid automatically or self-threading. Another is to provide 50 for adjustments to accommodate supply-

bobbins of different lengths. Another is to give the presser a capacity to rock transversely. Another is to provide for the convenient connection of the presser with the presser-lever, and disconnection therefrom. 60

The accompanying drawings show an illustrative embodiment of the features of the invention. In the said drawings,—

Fig. 1 is a side view of a tension device and a stand or bracket containing the said 65 features, showing also a supply-bobbin, a receiving spool, and certain parts belonging to a yarn-spooler.

Fig. 2 is a plan view of the tension device.

Fig. 3 is a view in vertical section in the 70 plane indicated by dotted line 3, 3, in Fig. 2.

Figs. 4 and 5, respectively, are views in section on line 4, 4, and 5, 5, of Fig. 1.

Having reference to the drawings,—

The supporting-stand or bracket comprises the main member 2, the bobbin-supporting member 3 and the member 4 supporting the tension means, the three members being combined with one another with capacity for adjustment to accommodate 80 bobbins of various lengths.

In this instance the main member 2 is provided with a notch 21 in its foot-portion to permit it to be mounted upon a supporting-rod 5 in a yarn-spooler, or the like, such member being held in place on such rod by a clamping screw 6.

The bobbin-supporting member, or hanger, 3, is applied in the present embodiment to member 2 near the lower end of member 2, 90 and is provided with a short spindle 7 of suitable size and length to enter the bore of a supply-bobbin 71. For adjusting the height at which the bobbin is supported, or to accommodate bobbins of different lengths, 95 a slot 22 is made in member 2 to receive the bolt 8 securing this hanger 6 to member 2. This slot extends lengthwise of member 2, at a slight outward inclination. It permits the hanger 3 to be moved up or down 100 until correctly positioned, notches 23, 23, being provided in one side of member 2 transversely of the slot (as indicated by dotted lines in Fig. 1) to receive a rib or ribs 24 (shown by dotted lines) formed on the 105 adjacent face of an ear of hanger 6 to hold the two parts firmly in adjusted relations.

I provide, in addition to the provisions described above for adjusting the hanger 3 up and down upon the member 2, a supplemen- 110

tary adjustment in the manner of combining members 2 and 4. To this end a slot 25 is formed in the upper end of member 2 for the bolt 26 which unites the two members. 5 This slot extends longitudinally of member 2, at a slight outward inclination, as shown. It permits the shifting of the clamping bolt 26, and consequently the head with its tension device, relative to the main stand-member 2. Notches 23 and a rib or ribs 24, shown by dotted lines, prevent accidental loss of adjustment. 10

The tension-producing means is located upon the head 41 of the upper member 4, the 15 said head having at its front end a fork constituting an open guide 9 which is occupied by the yarn or thread α passing from the supply-bobbin 71. The said yarn or thread passes up through the said open guide or 20 fork between the two prongs or branches 91, 92, thereof.

As in Letters Patent No. 1,393,926 a plate 12 of wear-resisting material is set flush in the top of the head, and the presser 13 of the 25 tension producing means normally bears against the surface of such plate. On its way toward the rear of the said head the yarn or thread passes between the presser and the said surface. The presser 13 in this 30 instance, like that of Patent No. 1,393,926, has the face portion 131 thereof constituted by a resilient spring member having transverse convex bearing ribs 130, 130, to contact with the running thread or yarn, the 35 yielding compression of the yarn between these bends and the underlying plate 12 operating to produce friction sufficient to establish the desired degree of tension of the yarn as it leaves the head. Herein, as in Letters

40 Patent No. 1,393,926, the elastic strip constituting the face-portion of the presser is secured at one of its ends to one end of the presser-body 14, the latter being pivotally mounted on a pintle 15 projecting transversely over the head, and parallel thereto, 45 from the presser-lever 16. This presser-lever 16 is pivoted to the side of member 4 at 17, just below the surface of the head, and is provided with a weight 18 which may be ad- 50 justed forward or backward along a slot 19 in the lever to either side of the pivot 17, to add to or reduce the pressure of the resilient spring or presser 13 upon the yarn or thread beneath it. The weight 18 is conveniently 55 adapted to be fixed at any point in the slot 19 by being drilled and tapped, as shown in Fig. 5, to receive a screw 20 having a flanged head at the back of the carrying lever, and also having its stem slabbed off on opposite 60 sides of its length so that it cannot revolve in the slot 19. Thus, rotation of the weight by hand in the proper direction serves quickly and easily to clamp it tightly to the lever 16 to hold the weight in place upon 65 the lever, or loosen it to permit of adjust-

ment of the weight along the slot 19 into the relations to lever-pivot 17 required to give the desired action upon the yarn or thread. The features just described providing for adjustment of the weight 18 are not claimed 70 herein because they are the subject of claim in my application for U. S. Letters Patent filed Mar. 21, 1925, Serial No. 17,253.

To prevent the accumulation of lint from the thread or yarn at the convex ribs 130, 130, of the presser, and guard against its 75 subsequent adherence to the yarn in the form of slubs, I provide slots or apertures 27, 28, one thereof in advance of the leading rib and the other thereof between the two ribs, 80 to permit downflow of portions of the current of air produced by the moving yarn or thread, carrying away such lint as may work off from the running yarn adjacent the ribs and between the presser and the plate 85 12. These slots or apertures 27, 28, may be of any desired shape or disposition. In the present embodiment two such slots or apertures are shown, corresponding with the 90 number of convex ribs 130, 130, provided on the particular presser illustrated, the forward slot 27 being formed through the metal of the head immediately in front of the forward end of plate 12, for the full width of said plate; and the aperture 28 being formed 95 directly through the plate 12 and underlying metal of the head, intermediate the two ribs. It has been found in practice that the running yarn passing over the slots or apertures creates downward currents of air there- 100 through, which serve very satisfactorily to carry any accumulated lint down with it and away from the yarn, clearing the yarn and the friction-creating parts of the device.

In the present invention I have combined 105 with the tension device as described above, means by which the thread or yarn from the bobbin is caused to enter automatically between the presser 13 and the plate 12, merely as a result of being entered between the 110 two prongs 91, 92, at the front of the head, and drawn in a general rearward direction in being wound upon the receiving spool 108, Fig. 1. This provision does away with all 115 loss of time incident to performing the threading operation by hand. In accordance with the invention, a deflecting edge 31, which may be of any suitable design and in its preferred form, as shown herein, com- 120 prises a bent wire, extends from a point to the left of the guide-notch 9 between prongs 91, 92, above the plane of the head, across the space lying between the said prongs and laterally outward to the right around the presser 13, thence rearwardly to a point at 125 the rear of the presser 13, as well as close to the said plane of the head and plate 12, having always a smooth curve toward the rear of the device, and then reversely across 130 behind the presser. Thus, when the thread

or yarn is drawn upward from the bobbin, entered between the two prongs 91 and 92, drawn in the general direction of the rear of the tension device, as in consequence of 5 being connected with and wound upon spool 108, the deflecting edge 31 deflects the yarn around the presser and also downward at the rear of the presser low enough to enter between the presser 13 and plate 12. At the 10 rear of the presser the deflecting edge is formed with an upward bend 32, forming a guide in line with the presser and into which the yarn or thread rises away from the plane 15 of the head. This guide 32 is located directly rearward of and closely adjacent to the rear end of presser 13. The lateral extremities of the convex ribs 130, 130, formed on the presser 13 preferably are beveled or rounded off at the side of the presser which 20 is toward the deflecting edge 31, so that the thread or yarn slips easily between the presser and the plate 12 in its effort to straighten its line of travel between guide 9 and the guide 32 in being drawn rearwardly. 25

In its preferred form the device also combines with the deflecting edge 31 a curved guard 33 of any suitable material, preferably a wire similar to that used for the said deflecting edge, and extending from a point on the prong 91, around the presser laterally outside of the said deflecting edge 31 and substantially parallel thereto. The rearward extremity of this guard 33 is engaged with 30 the head at the rear of the presser. As the yarn or thread is drawn rearwardly over the head and around the deflecting edge 31 for the purpose of causing the device to thread itself, this guard confines the yarn or 35 thread closely to the deflecting edge 31.

To limit the ballooning of the yarn as it unwinds from the bobbin, a web 46 is constructed on the under side of the head at 40 one side of the line of travel of the yarn or thread on its way from the bobbin to the guide 9, the prong 92 in the present embodiment, in position to be struck by the running yarn as soon as the latter begins to circle at all widely, to thereby curb or damp the ballooning action. 45

To provide for the lateral rocking aforesaid of the presser in conjunction with its longitudinal swinging movement, the presser and its supporting pindle or stud are fitted 50 to each other to give the presser capacity for such rocking. In this instance, as illustrated in Fig. 4, the said pindle or stud is barrel-shaped in that portion thereof on which the presser-body 14 is mounted, the hole through said body being parallel-sided, or substantially so. This permits the said rocking. 55

The presser-body preferably is composed 60 of a strip of spring material, steel for instance, one portion of the length thereof being bent back upon the other, as shown, a

bearing to fit the supporting pindle or stud being formed by bending the strip. In this instance such bearing is produced by a bend in the back-folded upper portion of the strip. The supporting pindle or stud is 70 formed with a shoulder for engagement with one edge of the presser-body, and with a head at its outer end for engagement with the other edge of the presser-body, said shoulder and head serving to prevent the 75 presser from becoming laterally displaced and from coming off the supporting pindle or stud. The elasticity of the material of the presser-body permits the upper and lower portions thereof to be sprung apart 80 through the application of slight force, so as to enable the head of the supporting pindle or stud to pass through between such portions in mounting the presser upon the said pindle or stud, and in dismounting it therefrom. 85

What is claimed as my invention is:—

1. A tension device comprising, in combination, a plate over which the yarn or thread is adapted to pass, a presser provided with a yielding face plate cooperating with said plate, said face plate having one or more convex ribs to press the yarn or thread against the said plate, and said plate first mentioned having a slot or slots adjacent the said convex rib or ribs through which portions of the current of air produced by the traveling yarn or thread escape carrying with them particles of lint. 90

2. A tension device comprising, in combination, a plate over which the yarn is adapted to pass, a presser cooperating with said plate, a yarn guide in line with said presser, means rendering the device self-threading comprising a deflecting edge extending from a point in front of and to one side of the guide and above the plane of the said plate, across in front of the presser to a point laterally beyond the presser, reversely across at the rear of the presser, and down to the plane of the said plate and a guard commencing at the opposite side of the first-named guide from that on which the said deflecting edge begins, and extending around to the rear of the presser. 100

3. A tension device comprising in combination, a plate, a presser cooperating with said plate, a yarn guide in front of said presser, and means rendering the device self-threading comprising a deflecting edge extending from a point in front of and to one side of the guide and above the plane of the said plate, across in front of the presser to a point laterally beyond the presser, reversely across at the rear of the presser, and down to the plane of the said plate, with an upward bend forming a guide for the yarn after it has passed around the said deflecting edge and entered between the presser and plate. 110

4. A tension device comprising, in combination, a plate, a presser cooperating with said plate, a yarn guide in front of said presser, means rendering the device self-threading comprising a deflecting edge extending across in front of the presser, along one side thereof, and reversely across at the rear thereof, and sloping downward to the surface of the said plate, with an upward bend forming a yarn guide at the rear of said presser, and a guard commencing at the opposite side of the first-named guide from that on which the said deflecting edge begins, and extending around to the rear of the presser.

5. In combination, a stand or bracket adapted for attachment to a spooling machine or the like, comprising a main member, a bobbin supporting member, and a member provided with tension means, and means combining both of the other members with the main member with capacity for individual adjustment thereof to suit bobbins of varying lengths, such means comprising upper and lower slots, bolts occupying such slots and fastening the other two members in adjusted position upon the main member, and intermeshing ribs and notches upon the respective members holding the members from turning displacement relative to one another.

6. A tension device comprising, in combination, a backing for the yarn or thread, a presser cooperating with the surface of said backing, and a presser-lever having a laterally extending pivotal stud on which said presser is mounted to swing, said stud shaped to permit lateral rocking of the presser in conjunction with its swinging movement.

7. A tension device comprising, in combination, a backing for the yarn or thread, a presser-lever, and a presser cooperating with the surface of the said backing and engaged with the presser-lever in manner

permitting swinging movement of the presser lengthwise of the yarn or thread and rocking movement transversely thereto.

8. A tension device comprising, in combination, a backing for the yarn or thread, a presser-mounting, and a presser having a yielding face which cooperates with the surface of said backing, said presser combined with said mounting in manner permitting swinging movement of the presser lengthwise of the yarn or thread and rocking movement transversely thereto.

9. A tension device comprising, in combination, a backing for the yarn or thread, a presser cooperating with the surface of said backing, and a carrying member having a laterally extending pivotal stud formed with a barrel-shaped portion on which said presser is mounted to swing longitudinally as well as rock transversely.

10. A tension device comprising, in combination, a backing for the yarn or thread, a presser cooperating with the surface of said backing and having a body portion composed of a spring strip folded back upon itself and bent to form a transversely extending bearing, and a headed supporting pintle or stud, the elasticity of said spring strip permitting the head of said pintle or stud to be forced through between the two portions of the strip in assembling and disassembling the parts.

11. A tension device of the character described comprising a head having a transverse presser-bearing, a presser, a presser-lever having the presser pivotally connected therewith and also having a transversely-extending lever-pivot which occupies the said presser-bearing, and a screw entering a threaded axial hole in the said lever-pivot, with a flange engaging with the head to prevent accidental transverse displacement of the presser-lever and presser.

JOSEPH BARNES.
